US00D706747S

(12) **United States Design Patent**
Yoshimura

(10) **Patent No.:** **US D706,747 S**
(b4) **Date of Patent:** **** Jun. 10, 2014**

(54) **PORTION OF DIGITAL AUDIO PLAYER**

(71) Applicant: **JVC Kenwood Corporation**, Yokohama (JP)

(72) Inventor: **Satoshi Yoshimura**, Sagamihara (JP)

(73) Assignee: **JVC Kenwood Corporation**, Kanagawa (JP)

(**) Term: **14 Years**

(21) Appl. No.: **29/445,890**

(22) Filed: **Feb. 19, 2013**

(30) **Foreign Application Priority Data**

Aug. 20, 2012 (JP) 2012-019826

(51) **LOC (10) Cl.** **14-01**

(52) **U.S. Cl.**
USPC **D14/209.1**

(58) **Field of Classification Search**
USPC D14/216, 221, 222, 223, 224, 224.1, D14/218, 172, 168, 194, 195, 217, 207, 304, D14/356, 496, 203.1–203.8, 188; 181/144, 181/145, 147, 148, 150, 153, 157, 198, 181/199; 381/300–302, 306, 333, 345, 343, 381/361–364, 386–388
